(57) **CLAIM**

The ornamental design for a vehicle taillight, as shown and described.

DESCRIPTION

FIG. 1 is a front left perspective view of a vehicle taillight according to the present invention.

FIG. 2 is a rear right perspective view of the taillight shown in FIG. 1.

FIG. 3 is a front view thereof.

FIG. 4 is a rear view thereof.

FIG. 5 is an enlarged left side view thereof.

FIG. 6 is an enlarged right side view thereof.

FIG. 7 is a top view thereof.

FIG. 8 is a bottom view thereof; and,

FIG. 9 is another front view thereof shown in use.

The broken lines illustrating environmental structure form no part of the claimed design.

1 Claim, 9 Drawing Sheets
